United States Patent Office.

MELVILLE D. JONES, OF SOMERVILLE, MASSACHUSETTS.

Design No. 3,953, dated April 5, 1870.

DESIGN FOR BRACKET.

The Schedule referred to in these Letters Patent and making part of the same.

I, MELVILLE D. JONES, of Somerville, county of Middlesex, State of Massachusetts, have invented and produced a new and original Design for a Bracket, of which the following is a specification.

The accompanying drawing is a side view of the bracket; the shaded portion represents the draught, and that part represented by the cross-section lace-work is sunken about one-sixteenth ($\frac{1}{16}$) of an inch.

I claim as my invention—
The design for a bracket, as shown.
MELVILLE D. JONES.
